(57) **CLAIM**

The ornamental design for a case for electronic device with rotatable and adjustable kickstand, as shown and described.

DESCRIPTION

FIG. 1 is a front perspective view of a first embodiment of a case for electronic device with rotatable and adjustable kickstand shown in a first configuration;

FIG. 2 is a front elevation view of the FIG. 1 device in the first configuration;

FIG. 3 is a rear elevation view of the FIG. 1 device in the first configuration;

FIG. 4 is a right-side elevation view of the FIG. 1 device in the first configuration;

FIG. 5 is a left-side elevation view of the FIG. 1 device in the first configuration;

FIG. 6 is a top plan view of the FIG. 1 device in the first configuration;

FIG. 7 is a bottom plan view of the FIG. 1 device in the first configuration;

FIG. 8 is a rear perspective view of the FIG. 1 device in the first configuration;

FIG. 9 is a rear elevation view of a second embodiment of a case for electronic device with rotatable and adjustable kickstand shown in the first configuration.

FIG. 10 is a front perspective view of the FIG. 1 device shown in a second configuration where the kickstand is rotated 180 degrees from its position in the first configuration;

FIG. 11 is a right-side elevation view of the FIG. 1 device in the second configuration;

FIG. 12 is a front perspective view of the FIG. 1 device shown in a third configuration where the kickstand is rotated 90 degrees clockwise from its position in the first configuration;

FIG. 13 is a right-side elevation view of the FIG. 1 device in the third configuration;

FIG. 14 is a front perspective view of the FIG. 1 device shown in a fourth configuration where the kickstand is rotated 90 degrees clockwise from its position in the first configuration;

FIG. 15 is a right-side elevation view of the FIG. 1 device in the fourth configuration; and,

FIG. 16 is an environmental view of the FIG. 1 device in the fourth configuration, illustrating how the device may be held by a user.

The broken lines represent portions of the structure that forms no part of the claim.
